UNITED STATES PATENT OFFICE.

LAWRENCE W. HORNE AND WARREN N. CRANE, OF NEW YORK, N. Y., ASSIGNEES OF
ONE-THIRD TO ALBERT C. HENRY.

AUTOMATIC TRAIN-STOPPING DEVICE.

1,142,256.

Specification of Letters Patent.

Patented June 8, 1915.

Application filed January 24, 1913. Serial No. 743,941.

To all whom it may concern:

Be it known that we, LAWRENCE WESLEY HORNE and WARREN NOBLE CRANE, citizens of the United States, residing, respectively, 5 at New York city, in the county of Kings and State of New York, and at New York city, in the county of Bronx and State of New York, have invented a new and useful Improvement in Automatic Train-Stopping 10 Devices, of which the following is a specification.

This invention relates to means of automatic steam control in locomotives in conjunction with the operation of the air 15 brakes, and our improvements comprise simple and inexpensive means, included in the train line of the usual brake system, whereby the steam throttle is caused to be automatically closed simultaneously with 20 the application of the brakes through the operation of a track tripping device.

In the drawings accompanying this application: Figure 1 is a side elevation of a portion of a locomotive, diagrammatically 25 exhibiting an air brake system, including our improvements; Fig. 2 is an end view thereof; Fig. 3 is an enlarged detail end view of our throttle control device; Fig. 4 is a side elevation of Fig. 3; Fig. 5 is a detail side elevation of the latch bolt and block with throttle levers; Fig. 6 is an end view of Fig. 5, and Fig. 7 is a top plan view of Fig. 5.

As premised, our improvement has relation to means for applying the air brakes and closing the steam throttle automatically in the event of the engineer passing a signal set at "danger" position. Under these conditions the usual track trip (not shown) is 35 raised in conjunction with the operation of the semaphore, and we provide a pendant valve handle D, carried, as by the locomotive, in the path of said track trip, to be swung by contact therewith, and thus to 40 open a cut-out valve, as C, in an extension C' of the train line pipe B. Connected to the train line pipe B is a auxiliary pipe A, which leads to a cylinder and latch lifting device shown in Figs. 3 and 4. The cylinder E has a connected, supporting frame E', which pivotally carries the toggle arms F, F', behind the cylinder head, a link F', mounted on the toggle pivot F², carrying piston rod H having piston H'. Between 45 the piston and cylinder head is a compres-

sion spring G. The lower toggle arm F pivotally carries a foot piece F³, having a guide stud F⁴, which extends into a vertical slot F⁵, whereby in the movement of the toggle arms, said foot piece F³ is operated 60 vertically.

It will be noted that we disconnect the throttle from the ordinary lever J' and that we arrange another short lever J, that we refer to as a main throttle lever, between 65 the throttle and the ordinary lever J' pivoting both levers to the same pin L' the reason for which will appear later.

A latch bolt I pivoted at I' to a main throttle lever J, is adapted for engagement 70 with a latching block K, that is mounted on an ordinary throttle lever J' used by the engineer. Said latch bolt is adapted to be released from engagement with the latch block through the toggle action referred to, 75 and it has a compression spring L to effect its return to normal position.

In the operation of the instrumentalities named it will be noted that while the train line pressure remains in cylinder E, the 80 toggle arms F, F' are inclined in the manner shown in Fig. 4 due to the extended position of piston rod H, spring G then being under compression. But when air pressure is relieved from the train line, either at the cut-out valve C, or elsewhere, whereby the 85 brakes are applied in the usual manner, by this means also the spring G is released, thus retracting the piston and piston rod and thereby straightening out the toggle arms 90 F, F', having the effect of extending the foot piece F³, causing it to act upon the latch bolt I, removing said latch bolt from engagement with the latching block K. Under this 95 action the main throttle lever is released from its connection with the ordinary lever that is used by the engineer, and said main throttle lever, thus released, is automatically pulled to the "off" position by steam action at the throttle valve, or by such other positive means as may be employed, thus shutting off the steam from the dry pipe. The latch bolt I, thus released, is immediately returned to its original position by the action 100 of the compression spring L, and the engineer can then again open the throttle valve by returning his lever to the "off" position, whereby the latching block K will slide under the latch bolt I, thus enabling the engineer to operate the main lever.

105

110

Obviously the spring G is stronger than spring L, to render the device operative. It is necessary for the engineer to close valve C by returning handle D to its normal closed position before he can release the brakes, and the occasion for this act is deemed important as likely to render engineers careful in obeying signals, to avoid the trouble consequent on the automatic operation aforesaid.

It will further be seen that a service pressure reduction of the train line pressure by the engineer will move the toggles to center, keeping the spring L compressed and permanently unlatching the main lever until the engineer releases the brakes.

We claim:

1. In an air brake system including a track trip a valve in the train line pipe adapted to be operated by said trip, a cylinder having a spring pressed piston connected with said train line pipe, a main throttle lever and an engineer's throttle lever removably connected thereto, together with means operated by the piston serving, when the train line valve is opened to disconnect said levers, permitting the main throttle lever to move to the "off" position.

2. An automatic steam shut off comprising a main throttle lever and an ordinary throttle lever having one general pivot, a latch bolt pivoted to said main throttle lever, a latching block on said ordinary throttle lever to receive said latch bolt, a cylinder included in an air brake system, a piston with a piston rod operating mechanism including

a toggle joint connected with said piston rod and a spring to retract said piston and thereby extend said operating mechanism upon a reduction of pressure in said cylinder, means whereby the extension of said operating mechanism rocks said latch bolt, releasing its engagement with said latching block, and a tensional return for said latch bolt.

3. A device of the character described having in combination with a throttle valve, a plurality of valve levers, means for engaging said levers for simultaneous operation, a source of fluid pressure means connected with said source and adapted to disconnect said levers one from the other upon the release of the pressure of said fluid, said means being held from operation by the pressure of the fluid, as and for the purpose set forth.

4. A device of the character described having in combination with a throttle of a plurality of levers adapted to be engaged together, a cylinder and piston operable therein, and an air supply connected to said cylinder, and means comprising a toggle connected to said piston, and a latch operated thereby for releasing the said levers by the lowering of the air pressure in said cylinder, as and for the purpose set forth.

In testimony whereof we have hereunto set our hands this 16th day of January, 1913.

LAWRENCE W. HORNE.
WARREN N. CRANE.
